DESIGN FOR A BINOCULAR OR THE LIKE

Willard T. Perkins, Irondequoit, N. Y., assignor
to Bausch & Lomb Optical Company, Rochester, N. Y., a corporation of New York

Application December 2, 1947, Serial No. 142,917

Term of patent 14 years

(Cl. D57—1)

To all whom it may concern:

Be it known that I, Willard T. Perkins, a citizen of the United States and a resident of the town of Irondequoit, county of Monroe, and State of New York, have invented a new, original, and ornamental Design for a Binocular or the like, of which the following is a specification, reference being had to the accompanying drawing, forming a part thereof.

Fig. 1 is a front view of a binocular or the like showing my new design.

Fig. 2 is a top plan view thereof.

Fig. 3 is a view of one of the eyepieces and body cap of the binocular or the like with parts shown in section.

The characteristic features of the design are shown in full lines on the drawings.

I claim:

The ornamental design for a binocular or the like, substantially as shown and described.

WILLARD T. PERKINS.
